UNITED STATES PATENT OFFICE

FRED FINKL, OF CHICAGO, ILLINOIS, ASSIGNOR TO A. FINKL & SONS COMPANY, OF CHICAGO, ILLINOIS, A CORPORATION OF ILLINOIS

DIPPER TOOTH

Application filed November 4, 1932. Serial No. 641,156.

This invention relates to improvements in dipper teeth of the detachable and renewable type, and has for its principal object to provide an improved construction and arrangement of tooth and base, including a replaceable wearing plate, whereby the base may be protected from excessive abrasion and its life thus prolonged.

As heretofore manufactured, dipper teeth of the detachable type have consisted of a base and a renewable tip or tooth suitably supported on and connected to the base. The tip is, of course, subject to severe abrasion, so is arranged to be renewed after its usefulness has been substantially impaired. It has been demonstrated, however, that in addition to the abrasion of the tip, the adjacent portions of the base are also more or less subject to wear and distortion which may, after long use, be sufficient to impair the usefulness of the base, and particularly where such wear or distortion may affect the supporting surfaces of the tip-receiving socket at the front end of the base.

In order to illustrate my invention, I have shown herein a base and dipper tooth of the general type disclosed in my prior application filed May 20, 1932, and bearing Serial No. 612,422, now Patent No. 1,890,981. When employed with the general type of removable tip therein illustrated, it will be understood that the bearing portions of the base immediately adjacent the removable tip are protected from excessive wear and abrasion by a separate plate which, although not subject to such excessive wear as the tip itself, may be replaced from time to time as needed to protect the base, and to maintain the supporting surfaces for the removable tip.

The invention may best be understood by reference to the accompanying drawings, in which

Figure 1 is a fragmentary side view of a dipper tooth in base assembly, constructed in accordance with my invention.

Figure 2 is an enlarged detail section taken on line 2—2 of Figure 1.

Figure 3 is a perspective view showing the under face of one of the wearing plates removed from the base.

Figure 4 is a fragmentary side view of a dipper tooth and base assembly showing a modified form of my invention.

Figure 5 is a detail section taken on broken line 5—5 of Figure 4.

Figure 6 is a perspective view showing the under face of one of the wearing plates shown in Figure 4, but removed from the base.

Referring now to the details of the embodiment of my invention shown in the drawings, 10 indicates the projecting portion of a tooth base which is secured to the dipper (not shown) in the usual manner. The detachable tip or tooth is indicated generally at 11 and comprises a head 12 and a shank 13. The head 12 is formed with two plane upper and lower faces 14, 14 converging forwardly to the point of the tooth, and two side faces 15, 15.

The head 12 also has two rearwardly converging plane faces 16, 16 which meet the rearward edges of the forwardly converging faces 14 at an obtuse angle, and merge into the shank 13 at the center and along the rounded edges 17, 17 extending laterally from opposite sides of the shank.

A pair of interlocking ribs 18, 18 are formed as elevations along the top and bottom of the shank 13 and merging into each rear face 16, said ribs extending longitudinally and centrally of the major axis of the tooth.

The shank 13 is substantially wider in a direction extending transversely of the tooth than in a vertical direction, as seen in Figure 3. A suitable aperture 19 extends through the rear end of the shank for engagement by a wedge pin 20, as indicated in Figure 1. The base 10 is provided with corresponding interlocking surfaces for receiving the tooth, including a socket 13^a to receive the shank 13, and inwardly converging walls 16^a, 16^a to receive the rear walls 16, 16 in seated engagement.

Referring now more particularly to the subject matter of the present invention, it will be observed that I provide a removable plate 25 in rabbeted or countersunk position along the outer surface 26 of the tooth base 10, said plate having its forward terminal

edge 27 arranged flush with the adjacent end surface 16^a forming a part of the tip-supporting surface of the base. In the form shown, two of such plates 25, 25 are employed, one at the top and the other at the bottom of the tooth. It will be understood that in some instances it may only be necessary to use one such plate, applied to the upper face of the tooth, since this upper face is usually arranged at a substantially inclined angle to the material being loaded into the dipper, and therefore is subject to much greater wear than the lower face. However, the construction arrangement of the two plates 25, 25 being similar, a description of one will suffice for an understanding of both.

The plate 25 is of the same transverse width as the base 10 and tip 11. An aperture 28 extends through the plate 25 centrally thereof to permit insertion and removal of the taper pin 20 which holds the tip 11 in the base 10. Suitable means are provided for detachably securing the plate to the base, in the form shown in Figures 1, 2 and 3 of the drawings, said means comprising a depressed boss 29 struck from the plate adjacent its rear end to receive a cap screw 30 passing through said boss and engaged in a screw threaded aperture 31 in said base. A suitable socket 29^a is, of course, formed in the rabbeted surface 26 of the base to receive the boss 29 as clearly shown in Figure 1. The forward edge of the plate 25 is secured by an overhanging lug 32 which herein is formed centrally of the plate and depending from the front margin thereof in alignment with the inclined front face 27. Said lug fits in a suitable recess 32^a formed in the inclined front face 16^a of the base so as to be flush with the latter, as clearly shown in Figure 1. In the form shown, the lug 32 is cut away at its central portion 18^a to fit over the rib 18 forming part of the shank 13. The arrangement is such that when the plate 25 is to be secured in place, the lug 32 is hooked into the socket 32^a, thus positioning the front edge of the plate centrally of the base. The rear end of the plate may then be secured in place by the cap screw 30 as shown in Figure 1.

With the parts in assembled position as shown, it will be observed that the front edge 27 of the plate and the associated front surface of lug 32 are seated flush with the adjacent inclined front surfaces 16^a forming part of the socket in which the head 12 is seated. With this construction, the plate 25 forms a substantial supplemental portion of the tooth socket along its outer margin.

With the construction just described, the plate 25 may be removed whenever it has become worn excessively along its outer surface. In ordinary usage it will be understood that the tip 11 may be replaced many times before it is necessary to renew the plate 25. Furthermore, the repeated shocks and

bending forces applied to each successive tip may have a tendency to spread the socket in which it is mounted, particularly along the outer edges thereof. This spreading action will be chiefly effective upon, and will be largely taken up by the front bearing surface 27 of the plate 25, but although said front surface may in time become somewhat distorted by the continued spreading action of the tip as just described, yet the socket can be quickly restored to its proper tip-supporting shape by the insertion of a new plate 25, whenever necessary.

In the form of renewable plate shown in Figures 4 and 6, both inclusive, the plate 40 is secured to the base by a pair of marginal flanges 41, 41 having dovetailed engagement in undercut grooves 42, 42 along the upper side edges of the rabbeted or recessed portion 43 on which said plate is fitted, as is best indicated in Figure 5. This form of plate may be attached when the tip is removed, by sliding said plate lengthwise to its fully seated position with the rear end 46 abutting the shoulder at the end of the rabbeted surface of the tooth. In this position the front edge 47 is supported flush with the adjacent socket-forming walls of the base in the same manner as described in connection with the form of plate shown in Figures 1 to 3, both inclusive.

Although I have illustrated and described certain embodiments of my invention, it will be understood that I do not wish to be limited to the exact constructions shown and describe herein, but that various changes and modifications may be made without departing from the spirit and scope of my invention as defined in the appended claims.

I claim:

1. A dipper tooth including a base and a detachable tooth, said tooth consisting of a head and a rearwardly projecting shank, said base having a socket including a surface for receiving said shank in close fitting engagement, and a wearing plate fitting on the outer face of said base contiguous to said head, and with the forward edge of said wearing plate flush with and supplemental to said socket-forming surface of said base, and means for securing said wearing plate to said base.

2. A dipper tooth including a base and a detachable tooth, said tooth consisting of a head and a rearwardly projecting shank, said base having a socket including a forwardly and outwardly inclined surface for receiving said shank in close fitting engagement, and a wearing plate fitting on the outer face of said base contiguous to said head, and with the forward edge of said wearing plate flush with and supplemental to said socket-forming surface of said base, and means for securing said wearing plate to said base.

3. A dipper tooth including a base and a

detachable tooth, said tooth consisting of a head and a rearwardly projecting shank, said base having a socket including a forwardly and outwardly inclined surface for receiving said shank in close fitting engagement, and a wearing plate fitting on the outer face of said base contiguous to said head, and with the forward edge of said wearing plate flush with and supplemental to said socket-forming surface of said base, and means for securing said wearing plate to said base, including a lug projecting inwardly in interlocking engagement with the adjacent part of said base.

4. A dipper tooth including a base and a detachable tooth, said tooth consisting of a head and a rearwardly projecting shank, said base having a socket including a forwardly and outwardly inclined surface for receiving said shank in close fitting engagement.

ment, and a wearing plate fitting on the outer face of said base contiguous to said head, and with the forward edge of said wearing plate flush with and supplemental to said socket-forming surface of said base, and means for securing said wearing plate to said base, including a lug projecting inwardly in alignment with said forward edge of said plate and in interlocking engagement with the adjacent part of said base.

5. A dipper tooth including a base and a detachable tooth, said tooth consisting of a head and a rearwardly projecting shank, and a wearing plate detachably secured to said base contiguous to, and in substantial alignment with, said tooth, and securing means for said plate including an integral overhanging portion having interlocking engagement with said base.

FRED FINKL.
